TYPEWRITING MACHINE

Filed July 1, 1921

2 Sheets-Sheet 2

Inventor: John Waldheim
by B. Stickney Attorney

UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed July 1, 1921. Serial No. 481,758.

To all whom it may concern:

Be it known that I, JOHN WALDHEIM, a citizen of the United States, residing in Elizabeth, in the conuty of Union and State of New Jersey, have invented certain new and useful Improvements in Typewriting Machines, of which the following is a specification.

This invention relates to sound-deadening casings or hoods for typewriting machines, the casing comprising a body part and a cover, provision being made for the line-space handle, the carriage-return handle and the carriage-release handle to project through a slot in the casing to the exterior thereof, and for the keyboard section of the machine to project through an opening in the lower part of the casing, so that the machine may be operated without raising the cover. The invention is in the nature of improvements which may be used with the parts shown in my prior application, No. 423,848, filed November 13, 1920 (now Patent No. 1,499,709, dated July 1, 1924), and the application of B. C. Stickney, No. 429,617, filed December 10, 1920 (now Patent No. 1,519,224, dated December 16, 1924).

An object of the present invention is the provision of means to prevent the handles, projecting out of the casing, from becoming accidentally in contact with things to the exterior of said casing. To this end, the casing is provided with an overhanging forward edge or eaves, the floor of which has a slot therein, through which the handles project toward the keyboard of the machine, so as to be protected under the eaves and to be in close reach of the hands of the typist at the keyboard. The floor of the eaves is formed by slot-closing cushions disposed horizontally relatively to each other, one of the cushions being supported on the cover to swing upwardly therewith, while the other cushion is supported on the body part. The line-space lever operates forwardly to compress the forward slot-closing cushion, which, however, is reinforced to provide the necessary resiliency to restore it to normal position.

A feature of the invention is the provision of a base or pad to support the casing and the typewriting machine within the casing, the pad being reinforced with a frame to assist in locating and securing the

casing to the pad. For this purpose, the base or pad may be comprised of layers of sound-deadening material, such as felt, secured to each other, and between which the reinforcing frame is disposed, the reinforcing frame comprising a main bar over which are disposed two cross-bars, the latter to be positioned under the feet of the machine when the casing is secured to the pad with the machine therein. Devices are also provided for securing the casing to the reinforcing frame of the pad. The casing is provided with internal abutments to fix the typewriting machine in position relatively to said casing, and, hence, relatively to the cross-bars and the pad.

When the casing is applied, there remains an opening at the front of the machine under the key-levers and from the key-lever guide-comb or plate to the supporting base or pad. It is another feature of this invention to provide a suitable plate which may readily be applied to the machine to close the opening from the bottom of the comb-plate to the base.

There remain openings due to the slots in the key-lever comb-plate, through which sounds may escape. It is a further feature of this invention to provide cushions between adjacent key-levers to keep closed the slots in the comb-plate, each key-lever when depressed spreading the adjacent cushions as it is operated.

The body part of the casing has a large front opening to enable the machine to be placed therein, the opening being closed by a removable plate. It is another feature of the invention to provide novel and efficient means for fastening the front plate upon the casing after the machine is inserted.

Other features and advantages will hereinafter appear.

In the accompanying drawings, Figure 1 is a front elevation, partly broken away, of the sound-deadening casing applied to an Underwood Standard typewriting machine.

Figure 2 is a plan view of the device shown in Figure 1, the cover part of the casing and parts of the typewriting machine being removed.

Figure 3 is a perspective view of the supporting base or pad.

Figure 4 is a detail view of the key-lever comb-plate with the sound-deadening means applied thereto.

Figure 5 is a plan view of the device 5 shown in Figure 4.

Figure 6 is a perspective view of the plate for closing the portion of the front opening between the bottom of the comb-plate and the supporting base.

10 Figure 7 is a side view, vertically sectioned, of the device shown in Figure 1.

The Underwood Standard typewriting machine comprises a main frame 9, supported above a base or pad 10 upon supporting feet 11, and a forward extension 12 of said main frame, in which are positioned banks of keys 13, which operate key-levers 14 to swing type-bars 15 to cause types carried by the type-bars to print against a platen 16 journaled in end walls 17 of a platen-frame 18 supported in a carriage 19. Said carriage is mounted for letter-feeding movement upon a front rail 20 and a rear rail 21 fixed to the main frame, said carriage 25 being provided with the usual line-space handle 22, carriage-return lever 23 and carriage-release lever 24, all of said levers comprising forwardly-extending portions and downwardly-extending portions (for a purpose to be described hereinafter). The platen may be rotated by knobs or finger-wheels 30 fixed to the ends of a shaft 31 upon which the platen is mounted, or by the usual line-space mechanism, of which only 35 the line-space handle 22 and slide 32 are shown. The carriage is provided with the usual pointer 33 operating over a scale 34 on the main frame, with which scale also co-operates the usual margin-stop 35.

40 To deaden the noise arising in the operation of typing, there is provided a sound-deadening casing or hood, which comprises a body part 40 and a cover part 41 hingedly connected at 42 to the rear of said body

45 part. The body part 40 comprises a rear wall 45, side walls 46 provided with lateral extensions 47, and a front wall composed of two laterally-spaced end sections 48, the space between said end sections being sufficiently large to permit the insertion of a typewriting machine therethrough and into said casing, the typewriter carriage operating over said extensions 47 to the right and left. When the machine has been inserted

55 in the casing, it is found that there are openings between the sides of the machine and the sections 48 of the casing, above the banks of keys adjacent the basket which houses the type-bars, below a guide or comb-plate 49 down to the supporting base 10, and in the comb-plate due to the slots 50 in which the key-levers operate.

60 For closing the front openings at the sides of the machine and adjacent the basket which houses the type-bars, the casing is

provided with a front plate 52, which is mounted upon the end sections 48 by finger-pieces 53, said front plate being provided with hooks 54 which pass through slots 55 in the end sections 48 behind said sections, 70 said front plate 52 lying adjacent the frame of the typewriter to close the openings at the sides thereof, and having a downwardly-extending arcuate portion 59 for closing the opening adjacent the type-holding basket. 75 The front plate 52 is provided with cut-out portions to permit ready access to the line-lock release-key 57 and the ribbon-color shift-key 58.

For closing the opening between the bottom of the comb-plate 49 and the supporting base 10, there is provided a plate, indicated generally by the numeral 62 (see Figures 6 and 7), said plate being provided with a horizontal portion 61, having flanges 85 63 for resting upon the upper surfaces of supporting feet 11 between said feet and the typewriter frame, so that screws 64 which are secured to said feet may pass through said flanges 63 to fasten said plate to the 90 machine. The plate 62 is provided with a vertical portion 65, which extends upwardly from horizontal portion 61, and a downwardly-extending portion 70, which closes the opening between the bottom of the typewriter frame and the supporting base 10. The plate 62 is provided with various openings 72 which permit various key-levers, which are located below the comb-plate, such as the back-space key-lever (not shown) and 100 the supporting arms or levers 73 of the space-bar 74, to operate therein. By an inspection of Figure 7, it will be seen that the vertical portion 65 of the plate 62 is slightly 105 in front of the lower edge of the key-lever comb-plate 49, thus leaving an opening between said vertical portion and said comb-plate. To close this opening, there is provided a plate 66 which rests upon ears 67 of the vertical portion 65, and which may 110 be secured to the plate 62 by screws 68 threaded into the ears 67, the plate 66 being attached after the plate 62 has been assembled on the machine. The plate 66 extends rearwardly and is provided at its rear end 115 with an upwardly-turned flange to abut against the front face of the key-lever comb-plate 49.

For closing the openings in the comb-plate, due to the vertical slots 50 in which the key-levers operate, there are provided cushions 75 of substantially the height of the comb-plate, said cushions comprising folds which lie between adjacent key-levers and are composed of sound-deadening material, such as plush, felt, or soft leather, which has sufficient resiliency to permit the folds to spread, so that adjacent cushions form a complete closure about the enclosed key-lever. The cushions are held in place by 120 125 130

means of upper and lower rods 76 passing through the two-ply margins of the cushions, said rods being held in place in flanges or brackets 77 fixed to the comb-plate.

5 When a key-lever 14 is depressed, as shown in Figure 4, the cushions permit an easy downward movement of said key-lever, but always closing the portion of the slot immediately below and immediately above said

10 key-lever.

The means described above, namely, the front plate 52, the plate 62, and the cushions 75, completely close the openings left in the body part of the casing after the 15 machine has been inserted therein. The casing is still open at the top. To close the top opening, there is provided the cover part 41 which comprises a rear wall 80, hinged to the rear wall 45 of the body part, and

20 side walls 78 having flanges 79 resting upon similar flanges 91 on the extensions 47, a strip of sound-deadening material 92 being interposed between the flanges, said rear wall 80 sloping downwardly and forwardly to form a top wall or ceiling 81,

25 said top wall having positioned therein a transparent plate 82 for permitting the interior of the casing to be viewed and terminating in a short front wall 83 positioned 30 forwardly from the front plate 52 of the body part to form an overhang or eaves 84. There is thus formed an opening, under the overhang, between front wall 83 and front plate 52. The various carriage-operat-

35 ing levers 22, 23 and 24, as previously described, extend forwardly and then downwardly to pass through the slot thus formed, and are protected under said overhang. To close all of the slot not actually occupied 40 by these levers, there are provided cushions 85 and 86 of sound-deadening material, the two-ply margins of said cushions being clamped between bars 87 to form units, which are mounted respectively upon the

45 rear face of front wall 83 to project rearwardly therefrom, and upon the top of front plate 52 to extend forwardly therefrom, so that said cushions contact. Since the carriage-release lever operates upwardly and 50 downwardly, it will not disturb the cushions in its operation, whereas, the line-space lever or handle 22 moves slightly forward when actuated and compresses the cushion 85. When the handle 22 is allowed to return, the

55 cushion 85 will be restored to normal. To add to the resiliency of cushion 85 to facilitate its restoration when the distorting force is removed, there is provided within cushion 85 a resilient tube 90.

60 The typewriting machine is thus completely enclosed at the front, sides, rear and top, and sounds arising in the typing operation may be further deadened by mounting the machine upon a sound-deadening base, such

65 as 10. The base 10 is composed of sound-

deadening material, preferably felt, which is not readily attachable to the casing and which would tend to yield beneath the weight of the typewriting machine, should it be attempted to lift the casing with the

70

machine resting on the pad. It is, therefore, desirable to provide means to enable the pad to be secured to the casing and to reinforce the base, particularly at the points which bear the weight of the machine and the

75

casing. For this purpose, the pad 10 comprises preferably an upper layer 93 and a lower layer 94, there being interposed between said layers a reinforcing frame composed of strips 95, 96 and 97.

80

The reinforcing strip 97 is seated into the upper surface of the lower layer 94 and extends laterally of the casing, the latter being attached to the strip 97 by means of screws 98, said

85

screws having shoulders 99 operating on flanges 100 fixed to the sides of the casing, the lower threaded portions 101 of the

90

screws 98 operating in threaded openings 102 in the strip to draw the strip and casing together. The upward movement of the

95

strip 97 and the downward movement of the casing are limited by the weight of the machine, whose feet 11 rest upon strips 95 and 96 positioned in the lower face of layer

100

93, the forward ends of the strips engaging under sections 48 of the front wall, and the rear ends engaging under the rear wall 45 of the casing. The strip 97 serves not merely as a support for the casing, but as

105

a means locating the casing on the base. The strips 95 and 96 are so positioned that feet 11 will rest upon said strips when the casing has been attached to strip 97, due to the fact that the casing is provided with front abutments 105 and rear abutments

110

106, which fix the position of the machine within the casing relative thereto. Means are thus provided for locating the casing relatively to the base, and for locating the machine relatively to the casing and hence

115

to the base. To support the casing more firmly upon the base, the body part may be

120

provided with flanges 110 forming an in-turned portion of its lower ends, whereby the casing may rest upon the base 10.

115

It will thus be seen that the casing, being once applied to the machine and a work-sheet having been inserted in the machine, all the ordinary typing operations may be performed without raising the cover. When a new work-sheet is to be inserted or corrections are to be made upon the sheet in the machine, or where the margin-stop 35 is to be set, the cover may be raised, the front plate 52 of the body part having its upper portion 84 extending forwardly a distance sufficient to permit free access to the carriage and its associated mechanism, such as the margin-stop 35.

125 Variations may be resorted to within the

130

scope of the invention, and portions of the improvements may be used without others.

Having thus described my invention, I claim:

- 5 1. The combination with a typewriting machine having a keyboard-extension and key-levers projecting forwardly into said extension, of sound-deadening means for said machine comprising cushions, one in each interval between successive key-levers, adjacent cushions contacting above and below the key-levers, passing therebetween and yielding locally as the key-levers are operated. 70
- 10 15. A sound-deadening casing for a typewriting machine, said machine comprising a carriage having various operating levers projecting forwardly therefrom, said levers having downward extensions at their outer ends, said casing comprising a body part and a cover part hinged at the rear to said body part, said body part having a front wall, said cover part having a front wall positioned forwardly from the front wall of the body part when the cover part is in lowered position, so that a slot is formed between said front walls through which said downward extensions pass. 75
- 20 25. A sound-deadening casing for a typewriting machine, said machine comprising a carriage having various operating levers projecting forwardly therefrom, said levers having downward extensions at their outer ends, said casing comprising a body part and a cover part hinged at the rear to said body part, said body part having a front wall provided with an opening large enough to permit passage of the machine therethrough and into said opening, and a removable front plate mounted on said front wall of the body part for closing said opening, said cover part having a front wall positioned forwardly from the front plate on the body part when the cover part is in lowered position, so that a slot is formed between said front wall of the cover part and said front plate on the body part through which slot said downward extensions pass. 80
- 30 35. A sound-deadening casing for a typewriting machine, said machine comprising a carriage having various operating levers projecting forwardly therefrom, said levers having downward extensions at their outer ends, said casing comprising a body part and a cover part hinged at the rear to said body part, said body part having a front wall provided with an opening large enough to permit passage of the machine therethrough and into said opening, and a removable front plate mounted on said front wall of the body part for closing said opening, said cover part having a front wall positioned forwardly from the front plate on the body part when the cover part is in lowered position, so that a slot is formed between said front wall of the cover part and said front plate on the body part through which slot said downward extensions pass. 85
- 40 45. A sound-deadening casing for a typewriting machine, said machine comprising a carriage having various operating levers projecting forwardly therefrom, said levers having downward extensions at their outer ends, said casing comprising a body part and a cover part hinged at the rear to said body part, said body part having a front wall provided with an opening large enough to permit passage of the machine therethrough and into said opening, and a removable front plate mounted on said front wall of the body part for closing said opening, said cover part having a front wall positioned forwardly from the front plate on the body part when the cover part is in lowered position, so that a slot is formed between said front wall of the cover part and said front plate on the body part through which slot said downward extensions pass. 90
- 50 55. A sound-deadening casing for a typewriting machine, said machine comprising a carriage having various operating levers projecting forwardly therefrom, said levers having downward extensions at their outer ends, said casing comprising a body part and a cover part hinged at the rear to said body part, said body part having a front wall provided with an opening large enough to permit passage of the machine therethrough and into said opening, and a removable front plate mounted on said front wall of the body part for closing said opening, said cover part having a front wall positioned forwardly from the front plate on the body part when the cover part is in lowered position, so that a slot is formed between said front wall of the cover part and said front plate on the body part through which slot said downward extensions pass. 95
- 60 65. A sound-deadening casing for a typewriting machine, said machine comprising a carriage having various operating levers projecting forwardly therefrom, said levers having downward extensions at their outer ends, said casing comprising a body part and a cover part hinged at the rear to said body part, said body part having a front wall provided with an opening large enough to permit passage of the machine therethrough and into said opening, and a removable front plate mounted on said front wall of the body part for closing said opening, said cover part having a front wall positioned forwardly from the front plate on the body part when the cover part is in lowered position, so that a slot is formed between said front wall of the cover part and said front plate on the body part through which slot said downward extensions pass. 100
- 70 75. A sound-deadening casing for a typewriting machine, said machine comprising a slotted guide-plate at the front thereof and key-levers extending forwardly through the slots in said guide-plate, said casing having an opening at the front to expose said guide-plate and permit said key-levers to extend outside of the casing, and a plurality of cushions interposed between successive key-levers adjacent said guide-plate to close the portions of the slots in the guide-plate not occupied by the key-levers to prevent escape of sound and to yield locally when the key-levers are operated. 105
- 80 85. A sound-deadening casing for a typewriting machine, said machine comprising a slotted guide-plate at the front thereof and key-levers extending forwardly through the slots in said guide-plate, said casing having an opening at the front to expose said guide-plate and permit said key-levers to extend outside of the casing, and means for closing the portions of the slots in the guide-plate not occupied by the key-levers to prevent escape of sound, said means comprising a plurality of cushions, formed by vertical folds of resilient sound-deadening material, interposed between adjacent key-levers adjacent said guide-plate, each set of adjacent cushions contacting to close all of the respective slot not occupied by the key-lever operating in said slot. 110
- 90 95. A sound-deadening casing for a typewriting machine, said machine comprising a slotted comb-plate at the front thereof and key-levers extending forwardly through the slots in said comb-plate, said casing having an opening at the front to expose said comb-plate and permit said key-levers to extend outside of the casing, means for closing the portions of the slots in the comb-plate not occupied by the key-levers to prevent escape of sound, said means comprising a plurality of cushions, formed by vertical folds of resilient material, interposed between adjacent key-levers, each set of adjacent cushions contacting to close all of the respective slot not occupied by the key-lever operating in said slot, and means for holding said folds at their tops and bottoms adjacent said comb-plate. 115
- 100 105. A sound-deadening casing for a typewriting machine, said machine comprising a slotted comb-plate at the front thereof and key-levers extending forwardly through the slots in said comb-plate, said casing having an opening at the front to expose said comb-plate and permit said key-levers to extend outside of the casing, means for closing the portions of the slots in the comb-plate not occupied by the key-levers to prevent escape of sound, said means comprising a plurality of cushions, formed by vertical folds of resilient material, interposed between adjacent key-levers, each set of adjacent cushions contacting to close all of the respective slot not occupied by the key-lever operating in said slot, and means for holding said folds at their tops and bottoms adjacent said comb-plate. 120
- 110 115. A sound-deadening casing for a typewriting machine, said machine comprising a slotted comb-plate at the front thereof and key-levers extending forwardly through the slots in said comb-plate, said casing having an opening at the front to expose said comb-plate and permit said key-levers to extend outside of the casing, means for closing the portions of the slots in the comb-plate not occupied by the key-levers to prevent escape of sound, said means comprising a plurality of cushions, formed by vertical folds of resilient material, interposed between adjacent key-levers, each set of adjacent cushions contacting to close all of the respective slot not occupied by the key-lever operating in said slot, and means for holding said folds at their tops and bottoms adjacent said comb-plate. 125
- 120 125. A sound-deadening casing for a typewriting machine, said machine comprising a slotted comb-plate at the front thereof and key-levers extending forwardly through the slots in said comb-plate, said casing having an opening at the front to expose said comb-plate and permit said key-levers to extend outside of the casing, means for closing the portions of the slots in the comb-plate not occupied by the key-levers to prevent escape of sound, said means comprising a plurality of cushions, formed by vertical folds of resilient material, interposed between adjacent key-levers, each set of adjacent cushions contacting to close all of the respective slot not occupied by the key-lever operating in said slot, and means for holding said folds at their tops and bottoms adjacent said comb-plate. 130

- slots in said comb-plate, said casing having an opening at the front to expose said comb-plate and permit said key-levers to extend outside of the casing, means for closing the portions of the slots in the comb-plate not occupied by the key-levers to prevent escape of sound, said means comprising a plurality of cushions, one cushion interposed in each interval between adjacent key-levers, the 10 cushions on opposite sides of each slot contacting to close all of the slot not occupied by the key-lever operating in said slot, and means for mounting said cushions adjacent the comb-plate.
- 15 9. A sound-deadening casing for a typewriting machine, said machine comprising a slotted comb-plate at the front thereof and key-levers extending forwardly through the slots in said comb-plate, said casing comprising a body part and a cover part, said body part having an opening at the front to expose said comb-plate and permit said key-levers to extend outside of the casing, means for closing the portions of the slots in the 25 comb-plate not occupied by the key-levers to prevent escape of sound, said means comprising a plurality of cushions interposed between adjacent key-levers, each set of adjacent cushions contacting to close all of the 30 respective slot not occupied by the key-lever operating in said slot, and means for mounting said cushions adjacent the comb-plate, said last-named means comprising rods mounted in said comb-plate, said rods passing through said cushions.
- 35 10. A sound-deadening casing for a typewriting machine, said machine comprising a slotted comb-plate at the front thereof and key-levers extending forwardly through the 40 slots in said comb-plate, said casing comprising a body part and a cover part, said body part having an opening at the front to expose said comb-plate and permit said key-levers to extend outside of the casing, means for closing the portions of the slots in the comb-plate not occupied by the key-levers to prevent escape of sound, said means comprising a plurality of cushions interposed between adjacent key-levers, each 45 cushion comprising a fold having two-ply margins adjacent the comb-plate, the folds of each set of adjacent cushions contacting to close all of the respective slot not occupied by the key-lever operating in said slot, and rods passing through said two-ply margins of the cushions, said rods being mounted in said comb-plate to hold said cushions in position adjacent the comb-plate.
- 50 11. A sound-deadening casing for a typewriting machine, said machine comprising a comb-plate at the front thereof and key-levers extending forwardly through said comb-plate, said machine resting on feet which support it above a base, there being 55 an opening between said comb-plate and the base, said casing comprising a body part and a cover part, said body part having an opening at the front extending from said comb-plate to the base to permit said key-levers to extend outside of the casing, and means for closing the opening between said comb-plate and the base, said means comprising a plate fixed at its upper end to said comb-plate and having its lower end contacting with said base, said plate having flanges whereby it 60 may be clamped between said supporting feet and the typewriting machine.
- 65 12. A sound-deadening casing for a typewriting machine, said machine comprising a comb-plate at the front thereof, key-levers extending forwardly through said comb-plate, and various levers extending forwardly below said comb-plate, said machine resting on feet which support it above a base, there being an opening between said comb-plate and the base, said casing comprising a body part and a cover part, said body part having an opening at the front extending from said comb-plate to the base to permit said key-levers to extend outside of the 70 casing, and means for closing the opening between said comb-plate and the base, said means comprising a plate fixed at its upper end to said comb-plate and having its lower end contacting with said base, said plate having flanges whereby it 75 may be clamped between said supporting feet and the typewriting machine.
- 80 13. A sound-deadening casing for a typewriting machine, said machine comprising a slotted comb-plate at the front thereof and key-levers extending forwardly through the slots in said comb-plate, said machine resting on feet which support it above a base, there being an opening between said comb-plate and the base, said casing comprising a front wall having an opening large enough to permit passage of the machine therethrough, a cover plate for closing said front wall, said cover plate having an opening extending from above the comb-plate to the 85 base, means for closing the portions of the slots of the comb-plate not occupied by the key-levers, said closing means comprising a single cushion between the key-levers of each pair of adjacent key-levers and means 90 for closing the opening between said comb-plate and the base.
- 95 14. A sound-deadening casing for a typewriting machine, said machine comprising a slotted comb-plate at the front thereof and key-levers extending forwardly through the slots in said comb-plate, said machine resting on feet which support it above a base, there being an opening between said comb-plate and the base, said casing comprising a front wall having an opening large enough to permit passage of the machine therethrough, a cover plate for closing said front wall, said cover plate having an opening extending from above the comb-plate to the 100 base, 105 means for closing the portions of the slots of the comb-plate not occupied by the key-levers, said closing means comprising a single cushion between the key-levers of each pair of adjacent key-levers and means 110 for closing the opening between said comb-plate and the base.
- 115 120 15. A sound-deadening casing for a typewriting machine, said machine comprising a slotted comb-plate at the front thereof and key-levers extending forwardly through the slots in said comb-plate, said machine resting on feet which support it above a base, there being an opening between said comb-plate and the base, said casing comprising a front wall having an opening large enough to permit passage of the machine therethrough, a cover plate for closing said front wall, said cover plate having an opening extending from above the comb-plate to the 125 base, 130 means for closing the portions of the slots of the comb-plate not occupied by the key-levers, said closing means comprising a single cushion between the key-levers of each pair of adjacent key-levers and means for closing the opening between said comb-plate and the base.

base, cushions mounted on said comb-plate, one cushion between the key-levers of each pair of adjacent key-levers, for closing the portions of the slots of the comb-plate not occupied by the key-levers, and a plate fixed to said comb-plate for closing the opening between said comb-plate and the base.

15. In combination, a sound-deadening casing for a typewriting machine, and a base upon which said casing and typewriting machine rest, said base being composed of sound-deadening material, and reinforcing strips within said base for bearing the weight of said casing and typewriting machine.

16. In combination, a sound-deadening casing for a typewriting machine, and a base upon which said casing and typewriting machine rest, said base being composed of layers of sound-deadening material secured to each other, and reinforcing strips positioned between said layers for bearing the weight of the casing and typewriting machine.

25. 17. In combination, a sound-deadening casing for a typewriting machine, a base upon which said casing and typewriting machine rest, said base being composed of sound-deadening material, and reinforcing strips within said base for bearing the weight of said casing and typewriting machine, and means whereby said casing may be fastened to said base, said means comprising fastening members carried by said casing and engaging one of said reinforcing strips.

18. In combination, a sound-deadening casing for a typewriting machine, a base upon which said casing and typewriting machine rest, said base being composed of sound-deadening material, and reinforcing strips within said base, and means whereby said casing may be fastened to said base, said means comprising fastening members connecting said casing to said reinforcing strips.

45. 19. In combination, a sound-deadening casing for a typewriting machine, a base upon which said casing and typewriting machine rest, said base being composed of sound-deadening material, and reinforcing strips within said base, and means whereby said casing may be fastened to said base, said means comprising fastening members engaging said casing and one of said reinforcing strips to draw said casing and strip together, the other of said reinforcing strips supporting the typewriting machine and being positioned within the base above the strip which supports the casing, to force the latter strip downwardly against the action of the fastening means.

60. 20. In combination, a sound-deadening casing for a typewriting machine, a base upon which said casing and typewriting machine rest, said base being composed of

sound-deadening material, and reinforcing strips within said base for bearing the weight of said casing and typewriting machine, and means whereby said casing may be fastened to said base, said means comprising fastening members carried by said casing, one of said reinforcing strips being positioned laterally of the casing, said fastening members engaging the lateral strip to draw said casing and strip together, the other of said reinforcing strips being positioned longitudinally of the casing above said lateral strip, for supporting the typewriting machine and forcing the lateral strip downwardly against the action of the fastening means.

70. 21. In combination, a sound-deadening casing for a typewriting machine, a base upon which said casing and typewriting machine rest, said base being composed of sound-deadening material, and reinforcing strips within said base for bearing the weight of said casing and typewriting machine, and means whereby said casing may be fastened to said base, said means comprising flanges fixed to said casing, and fastening members passing through said flanges and threaded at one end, one of said reinforcing strips having threaded openings in which said fastening members engage.

75. 22. In combination, a sound-deadening casing for a typewriting machine, a base upon which said casing and typewriting machine rest, said base being composed of sound-deadening material, and reinforcing strips within said base for bearing the weight of said casing and typewriting machine, and means whereby said casing may be fastened to said base, said means comprising flanges fixed to the sides of said casing, and fastening members passing through said flanges and threaded at one end, one of said reinforcing strips being positioned laterally of the casing and having threaded openings in which said fastening members engage.

80. 23. In combination, a sound-deadening casing for a typewriting machine, a base upon which said casing and typewriting machine rest, said base being composed of layers of sound-deadening material, and reinforcing strips positioned between said layers for bearing the weight of the casing and typewriting machine, and means whereby said casing may be fastened to said base, said means comprising fastening members carried by said casing, one of said reinforcing strips being imbedded in the upper surface of the lower layer of the base and positioned laterally of the casing, said fastening members engaging said lateral strip to draw said casing and strip together, the other of said reinforcing strips being positioned longitudinally of the casing in the lower surface of the upper layer of the

base above said lateral strip, for supporting the typewriting machine and forcing the lateral strip downwardly against the action of the fastening means.

24. In combination, a sound-deadening casing for a typewriting machine, a base upon which said casing and typewriting machine rest, said base being composed of sound-deadening material, and reinforcing strips within said base for bearing the weight of said casing and typewriting machine, means whereby said casing may be fastened to said base and positioned relatively thereto, said means comprising fastening members carried by said casing and threaded at one end, one of said reinforcing strips having threaded openings in which said fastening members engage, and means whereby said machine may be positioned within said casing relatively to said casing and said base.

25. A casing for a typewriting machine, the typewriting machine comprising a carriage having a forwardly and downwardly-extending finger-piece, the casing comprising an overhang at the front thereof, said overhang having a slot in its bottom wall through which projects the downwardly-extending portion of the finger-piece on the carriage.

26. The combination with a typewriting machine having a keyboard-extension and key-levers projecting forwardly into said extension, of sound-deadening means for said machine comprising cushions, one in each interval between successive key-levers, adjacent cushions contacting above and below the key-levers, passing therebetween and yielding locally as the key-levers are operated, and a sound-deadening shield secured to said machine and preventing the escape of sound between said cushions and a base when the typewriting machine is placed on said base.

27. A casing for a typewriting machine, the typewriting machine comprising a carriage having forwardly and downwardly-extending finger-pieces, said casing comprising a body part having a front wall, and a cover having a front wall positioned forwardly of the front wall of the body part forming an overhang when the cover is closed, the adjacent edges of the front walls providing a slot through which the finger-pieces project downwardly, and slot-closing means arranged lengthwise of the slot and comprising two oppositely-disposed cushion elements, said elements being disposed at substantially the same elevation.

28. A casing for a typewriting machine, the typewriting machine comprising a carriage having forwardly and downwardly-extending finger-pieces, said casing comprising a body part and a cover, the body part comprising walls including a front

wall, the front wall having an opening therein to enable the machine to be inserted into the casing, a releasable front plate to close the opening not occupied by the machine, and an overhang on said casing, said overhang being formed by the forward edge of the cover, said finger-pieces projecting downwardly behind the forward edge of the cover and in front of the releasable plate.

29. The combination with a casing for a typewriting machine, of a pad to support said casing, a reinforcing frame in said pad, means to locate the casing relatively to the reinforcing frame in said pad, and means to locate the machine relatively to the casing and to said reinforcing frame.

30. The combination with a typewriting machine, of a sound-deadening casing, a pad to support the machine and the casing, a reinforcing structure comprising a main bar and two cross-bars arranged above the main bar, devices to engage the casing and the pad to locate the casing on said pad, and devices to locate the machine relatively to the reinforcing structure of the pad.

31. The combination with a typewriting machine having supporting feet, of a sound-deadening casing, a pad to support the casing and the machine, a reinforcing frame in said pad, said reinforcing frame comprising a main bar and two cross-bars disposed above the main bar, devices to engage the casing and the reinforcing frame to locate the casing on the pad, and devices on the casing to locate the machine so as to bring the supporting feet of the machine over the cross-bars of the reinforcing frame.

32. A sound-deadening casing for a typewriting machine comprising key-levers, a guide-plate at the front of the machine having slots through which the key-levers extend, feet to support the machine above a base, said casing comprising a body part to rest on said base and having a front wall provided with an opening to permit the machine to be placed within the casing and a releasable front plate to close the portions of the opening in the front wall at the sides of the machine, and a plate removably attached to the machine at its front to close the opening between the guide-plate and the base.

33. A sound-deadening casing for a typewriting machine, said machine comprising key-levers, a guide-plate at the front of the machine for said key-levers, said guide-plate having slots through which the key-levers extend, removable feet to support the machine above a base, there being an opening beneath the guide-plate, said casing comprising a body part having a front wall with an opening therein to permit the machine to be placed within the casing, a releasable front plate to close the opening in the front wall at the sides of the machine, a plate to

close the opening beneath the guide-plate, and ears on said third-named plate, said ears extending beneath the machine so that the plate may be readily attached by the 5 movable feet.

34. A sound-deadening assemblage for a typewriting machine comprising key-levers, a guide-plate at the front of the machine for said key-levers, said guide-plate having slots 10 through which the key-levers extend, feet to support the machine above a base, there being an opening beneath the guide-plate, said assemblage comprising a casing having a front wall with an opening therein to permit 15 the machine to be placed within the casing and a releasable front plate to close the opening in the front wall at the sides of the machine, means secured to the typewriting machine for closing the portions of the slots 20 in the guide-plate not occupied by the key-levers, and means secured to the typewriting machine for closing the opening between the guide-plate and the base.

35. The combination with a sound-deadening casing for a typewriting machine comprising key-levers, a guide-plate at the front of the machine for said key-levers, said guide-plate having slots through which the key-levers extend, and feet to support the 25 machine above a base, there being an opening beneath the guide-plate, said casing comprising a body part having a front wall with an opening therein to permit the machine to be placed within the casing, of a 30 front plate releasably attached to the casing to close the portions of said opening at the sides of the machine, a plurality of cushions interposed between adjacent key-levers, each 35 pair of adjacent cushions contacting to close all of the corresponding slot not occupied 40 by the key-lever operating therein, and a plate detachably connected with the machine to close the portion of said opening beneath the guide-plate.

36. The combination with a typewriting machine and a sound-deadening casing therefor, said machine having key-levers with vacant spaces therebetween, and guiding 45 means for said key-levers, said key-levers 50 vers extending into a forward extension of the machine, the casing comprising walls in-

cluding a front wall, the front wall having a cut-out through which the forward extension of the machine projects, of means disposed between the key-levers to prevent the 55 leakage of sound from the casing around the key-levers.

37. The combination with a typewriting machine and a sound-deadening casing therefor, said machine having key-levers 60 with vacant spaces therebetween, and guiding means for said key-levers, said key-levers extending into a forward extension of the machine, the casing comprising walls including a front wall, the front wall having 65 a cut-out through which the forward extension of the machine projects, of means including co-operating cushions, one disposed between the key-levers of each pair of adjacent key-levers, to prevent the escape of 70 sound from the casing between the top of the cut-out and a line below the lower limit of movement of said key-levers.

38. The combination with a typewriting machine and a sound-deadening casing 75 therefor, said machine having key-levers with vacant spaces therebetween, and guiding means for said key-levers, said key-levers extending into a forward extension of the machine, the casing comprising walls 80 including a front wall, the front wall having a cut-out through which the forward extension of the machine projects, of co-operating cushions, one between the key-levers of each 85 pair of adjacent key-levers, to prevent the escape of sound from the casing around the key-levers, said cushions co-operating with the front wall above the cut-out, and means including a plate disposed beneath the cushions to prevent the escape of sound beneath 90 the cushions.

39. In combination, a sound-deadening casing for a typewriting machine, and a base upon which said casing and typewriting and machine rest, said base comprising 95 sound-deadening material and a reinforcing frame formed of transversely and forwardly-and-rearwardly extending bars.
